UNITED STATES PATENT OFFICE.

THOMAS THOMPSON, OF PAWTUCKET, RHODE ISLAND, ASSIGNOR TO AMERICAN TEXTILE COMPANY, OF PAWTUCKET, RHODE ISLAND, A CORPORATION OF RHODE ISLAND.

VARIABLE-SPEED BOBBIN-WINDING MACHINE.

1,126,317.

Specification of Letters Patent.

Patented Jan. 26, 1915.

Application filed July 5, 1913. Serial No. 777,399.

To all whom it may concern:

Be it known that I, THOMAS THOMPSON, a citizen of the United States, residing at Pawtucket, in the county of Providence and 5 State of Rhode Island, have invented a new and useful Improvement in Variable-Speed Bobbin-Winding Machines, of which the following is a specification.

This invention relates to certain new and 10 useful improvements in variable speed bobbin winding machines, and the object thereof is to provide a machine of the type mentioned in which a large number of bobbins may be uniformly wound in unison; to provide means which positively indicates the 15 quantity of yarn wound on each bobbin, and to also provide means to allow the indicating means to be moved back to zero and the yarn supplying drum rotated backwardly to enable the machine to wind a new set of 20 bobbins.

Further, the invention aims to provide a novel and improved means for effecting decrease of the speed of rotation of the bobbins as the diameter of the yarn wound 25 thereon increases.

In the drawings—Figure 1 is a top plan view of a machine constructed in accordance 30 with the invention. Fig. 2 is a side elevation. Fig. 3 is an end elevation, partly broken away. Fig. 4 is a detail view, partly in section. Fig. 5 is a section taken on the line 5—5 of Fig. 4, and Fig. 6 is a section taken on the line 6—6 of Fig. 1.

35 The end uprights 1 of the frame support the bed 2 of the machine, on which bed the several parts constituting the invention are mounted.

A yarn supplying drum 3 is mounted on a 40 shaft 6 that is journaled in bearings 4, the latter being supported from the bed 2, the drum being arranged at right angles to a shaft 5 which shaft extends longitudinally of the bed.

45 The shaft 6 is provided with a worm 7 which meshes with a worm gear 8 that is loosely mounted on the shaft 5. A spring pressed pawl 8' is carried by the worm gear 8 and engages with a ratchet 9 that is rigidly secured to the shaft 5, permitting the shaft 5 to be revolved independently of the worm 7 and gear 8 in an obvious manner. The rotation of the shaft 5 by the aforementioned means causes the hand 10 of an indicator 11

to have corresponding movement for a purpose later herein set forth, the hand 10 being actuated by any suitable gearing (not shown).

A driving shaft 12 has a fly wheel 13 on its outer end and is provided with a loose pulley 14 and a fast pulley 15, the belt (not shown) being shifted by a shipper 16, which may be controlled by a foot-operated treadle 17 that has suitable connections with the shipper 16. The shaft 12 is mounted in 65 bearings 18 and is permitted limited sliding movements in said bearings, and is held in normal position by a spring 19 that encircles shaft 12 and abuts a rigid collar 19' on the shaft and the outermost bearing 18. 70

A cam member 20 is slidably secured to the shaft and is normally held by the spring in engagement with the inner bearing 18, the cam member having a cam face 21 which engages with a similar cam face 22 on a 75 complementary cam member 23 that is rotatable relative to the shaft 12 and abuts a collar 24 rigidly attached to shaft 12.

A hand engaging member 25 is secured to the cam member 23 to permit of movement 80 thereof relative to the cam member 20.

A friction disk 26 is rigidly attached to the inner end of the shaft 12 and is engaged by a drive friction gear 27 that slides on and rotates a shaft 28 that is disposed at right 85 angles to the shaft 12. The friction gear 27 is circumferentially grooved at 29 and receives in said groove the arms of the forked end 30 of a shipper 31. The shipper 31 is mounted on the upright arm 32 of a slide 33 90 the latter having one end guided in a slotted member 34 and having a slot 35 in its other end, in which slot a projection 36 extends, which projection may be loosely mounted on the inner end of the shaft 5. The shaft 5 95 has a cam 37 thereon the tail of which engages with a roller 38 on the slide 33 in order that the latter may be operated from the shaft 12 to vary the relationship between the friction gear 27 and the disk 26 in order to 100 obtain desired speed of the friction gear 27. A coil spring 33' is secured to the slide and to a support 34' on the bed 2 to normally move the slide inwardly.

The shaft 28 carries a series of bobbins 39 105 which are of the double disk type commonly used in connection with lace machines, and also carries a balance wheel 40. A thread

or yarn guide 41, which has its upper edge serrated to engage the threads and guide same, is attached to the bed 2 and serves to guide the yarn from the drum 3 to the individual bobbins 39.

In operation, the shipper 16 is moved to the fast pulley 15 to thereby rotate the disk 26, which latter rotates the friction gear 27 and thereby the shaft 28 that carries the bobbins 39. The yarn is taken from the drum 3 and wound on the bobbins 39 by the movement of the latter. Rotation of the drum 3 effects movement of the shaft 5 by the aforementioned connections between the shafts 6 and 5, whereby the indicator hand is moved to indicate the number of yards of yarn wound on the bobbins. The movement of the shaft 5 causes the cam 37 thereof to gradually move the slide 33 against the action of its spring 33' outwardly, thus causing the friction gear 27 which is in connection with the slide 33 to be moved inwardly relative to the periphery of the disk 26 so as to gradually decrease the speed of rotation of the shaft 28 and thereby that of the bobbins as the diameter of the bobbins increases due to the increased winding thereon. To facilitate the removal of the bobbins and the backward rotation of the drum, after a predetermined amount of thread has been wound on the bobbin, after cutting of the thread, the handle 25 of the clutch is turned to cause the cam member 23 to ride on the cam face of the cam member 20, thus moving the disk 26 against the tension of the spring 19 away from the friction gear 27, whereupon the drum may be rotated backwardly and the indicator reset at zero before operating the new layer or set of bobbins.

Having thus described my invention, I claim as new and desire to secure by Letters Patent,--

1. In a device of the type set forth, a bed, a drum at one end of the bed, a worm connected to the drum, a shaft at right angles to the drum having an indicator operatively connected thereto, a worm gear in mesh with the worm and loosely mounted on the shaft, a ratchet rigid on the shaft, a spring pressed pawl carried by the worm gear of the shaft and being for engagement with the ratchet

of the shaft, a driving shaft having a friction disk thereon, a bobbin carrying shaft having a friction gear for engagement with the disk, a spring pressed slide which has means for shifting the position of the friction gear relative to the disk, and a cam on the first named shaft to engage said slide to cause the same to move the friction gear toward the disk center.

2. In a device of the type set forth, driving means including a disk, a pulley for engagement with the disk, a shaft to which the pulley is connected so as to slide thereon but to rotate the shaft therewith, a slide connected to the pulley so as to shift the same along the length of the shaft, a projection on the slide, a spring connected to the slide for moving the same inwardly, a yarn carrying drum, a shaft in operative connection with the drum and actuated by the movements of the latter, and a cam on the shaft which engages the slide and governs the outward movement thereof.

3. In combination with a yarn supplying drum, a shaft operatively connected to the drum, a bobbin carrying shaft, a friction gear slidable on the second shaft for rotating the same, means to drive the friction gear, a slide having a projection connected to the friction gear for sliding the same on the shaft thereof, a cam on the first named shaft for actuating the slide, and means to move the slide outwardly when the cam moves away from the projection on the slide.

4. In a bobbin winding machine, a yarn carrying drum, a shaft actuated by the drum movements, a disk, a bobbin carrying shaft arranged parallel to the disk and having a slidable pulley engaged with the disk, a slide connected to the pulley to move the latter radially of the disk, and means on the first named shaft to engage the slide to move same and therewith the pulley radially of the disk.

In testimony whereof I have signed my name to this specification in the presence of two subscribing witnesses.

THOMAS THOMPSON.
